(57) **CLAIM**The ornamental design for a control handle as shown and
described.

DESCRIPTION

FIG. 1 is a perspective view of a control handle showing the
new design.

FIG. 2 is a front view thereof.

FIG. 3 is a rear view thereof.

FIG. 4 is a left-side view thereof.

FIG. 5 is a right-side view thereof.

FIG. 6 is a top view thereof; and,

FIG. 7 is a bottom view thereof.

In these drawings, the solid lines illustrate the claimed
ornamental design, whereas the broken lines illustrate
unclaimed subject matter and form no part of the claimed
design. The dash-dot-dash broken lines in FIGS. 1-7 repre-
sent boundary lines and form no part of the claimed design.**1 Claim, 7 Drawing Sheets**(56)
